Term of patent 7 years

(Cl. D87—5)

Fig. 1

Fig. 2

Figure 1 is a perspective view of a carrying case for slide projector or the like, showing my new design;

Figure 2 is an end elevational view;

Figure 3 is an end elevational view;

Figure 4 is a top plan view.

The essential features are shown in full lines wherein the distinguishing characteristics of my design reside in the outwardly tapering relatively shallow lower one-third in combination with the reversely tapered upper two-thirds, and a circumferential dividing strip, all as shown.

I claim:

The ornamental design for a carrying case for slide projector or the like, substantially as shown and described.
